COMBINED TABLE AND DUAL DESK UNIT

Raymond C. Barnes, Temple, Tex., assignor to American
Desk Manufacturing Company, Temple, Tex., a cor-
poration of Texas

Filed May 29, 1968, Ser. No. 12,131

Term of patent 14 years

Int. Cl. D6—01

U.S. Cl. D33—7

FIG. 1

FIG. 2

FIG. 3

FIG. 4

FIG. 5

FIGURE 1 is a perspective view of a combined table and dual desk unit embodying my new design;

FIGURE 2 is an elevational view thereof looking in the direction of the arrow 2 in FIGURE 1;

FIGURE 3 is an elevational view thereof looking in the direction of the arrow 3 in FIGURE 1, the elevation as viewed oppositely to FIGURE 3 being a mirror image of FIGURE 3;

FIGURE 4 is an elevational view thereof looking in the direction of the arrow 4 in FIGURE 1; and

FIGURE 5 is a bottom plan view thereof.

I claim:

The ornamental design for a combined table and dual desk unit, substantially as shown and described.
